US0D1052527S

(12) **United States Design Patent** (10) Patent No.: **US D1,052,527 S**
(45) Date of Patent: ** Nov. 26, 2024

(54) **INDUCTIVE APPARATUS**

(71) Applicant: **Pulse Electronics, Inc.**, San Diego, CA (US)

(72) Inventors: **Thuyen Dinh**, San Diego, CA (US); **Mohammad Saboori**, San Diego, CA (US); **Aurelio Gutierrez**, San Diego, CA (US); **Collin Kneifl**, San Diego, CA (US); **Thomas Rascon**, San Diego, CA (US); **Farid Hamidy**, San Diego, CA (US)

(73) Assignee: **PULSE ELECTRONICS, INC.**, San Diego, CA (US)

(**) Term: **15 Years**

(21) Appl. No.: **29/780,725**

(22) Filed: **Apr. 26, 2021**

Related U.S. Application Data

(62) Division of application No. 16/518,874, filed on Jul. 22, 2019, now abandoned, which is a division of application No. 14/550,739, filed on Nov. 21, 2014, now abandoned.
